UNITED STATES PATENT OFFICE.

GEORGE W. BUTTON AND MILTON SIERAD, OF NEW YORK, N. Y.

DISPENSER AND CONTAINER FOR PERFUMES.

1,420,965.

Specification of Letters Patent. Patented June 27, 1922.

Application filed July 6, 1921. Serial No. 482,705.

To all whom it may concern:

Be it known that GEORGE W. BUTTON and MILTON SIERAD, citizens of the United States, residing at New York city, in the county 5 of New York and State of New York, have invented certain new and useful Improvements in a Dispenser and Container for Perfumes, of which the following is a specification.

10 Our invention relates to a new and improved combination container and dispenser for perfumes and other aromatic and volatile fluids.

It has heretofore been customary to sell 15 such fluids in ordinary bottles which were inconvenient to carry along in an ordinary handbag and which frequently allowed the contents to spill out. In addition, whenever the stopper of such bottle was removed 20 for the purpose of pouring out some of the perfume, the more volatile ingredients vaporized, which impaired the fine quality of the perfume, since expensive perfumes are composed of a blend of a great many ingredients, all of which should be preserved in 25 their original proportions.

In addition, with the ordinary bottles or containers heretofore in use, it was difficult 30 to pour out only a drop or two of the perfume which is usually all that is required, so that a good deal of waste occurred.

In addition, the perfume when poured 35 out would be locally applied upon the handkerchief of the user or the like, whereas it is highly desirable that this perfume should be applied with as large an area as possible.

One of the objects of my invention is to provide a combination container and dispenser so that the perfume can be utilized 40 without removing the cork or stopper.

Other objects of our invention are to provide a combination device of the kind specified in which it is impossible for the perfume to spill out.

45 Other objects of our invention generally speaking, are to remedy the disadvantages before mentioned.

The following description and drawings illustrate preferred embodiments of our invention in which, Fig. 1 is an elevation.

Fig. 2 is a vertical central section of Fig. 1.

Fig. 3 is a vertical central section of the casing.

Fig. 4 is a vertical central section of the bottle. 55

Fig. 5 is an enlarged vertical central section showing the top of our device.

Fig. 6 is a top view of Fig. 5.

Fig. 7 is a section along the line 7—7 of Fig. 5. 60

Fig. 8 is a top view of the hollow slotted plug with the internal wick spread out.

Fig. 9 is a vertical central section of another embodiment.

Fig. 10 is a vertical central section illustrating another embodiment of my invention. 65

Fig. 11 is a sectional view along the line 11—11 of Fig. 9.

Fig. 12 is a sectional view along the line 70 12—12 of Fig. 10.

Our combination device consists of a casing 1 which can be made of any suitable metal which can be brightly polished and ornamented as desired. This casing 1 substantially encloses the bottle 2 made of glass or other suitable material and containing the perfume or similar fluid. As seen in Fig. 2, the top of the fluid is preferably below the bottom of the cork or stopper 3. 80 The fluid is normally below the bottom of the cork or stopper 3, because even if the receptacle is filled as much as possible, the top of the fluid in a very short time is below the bottom of the cork 3. 85

As seen more particularly in Fig. 5, the cork or stopper 3 may be provided with a metal cap 9 so as to strengthen that part thereof which projects above the casing 1. The cork 3 is perforated and in the embodiment shown in Fig. 5, a hollow and slotted plug 5 having a solid head 4 is inserted therein. As seen more particularly in Figs. 7 and 8, a wick 6 made of any suitable absorbent fabric is thrust into the hollow of 95 the slotted plug 5, being held there by friction and as seen in Fig. 7, the outer wall of the plug 5 is surrounded by a substantially cylindrical piece of absorbent fabric 6', which is provided with an extension 7 100

at the top of the metal cap 9. A washer 8 made of some suitable absorbent material is held between the top of the cap 9 and the solid head 4, said solid head 4 being 5 tightly pressed against the said washer 8, whereby the said washer 8 is firmly pressed and tightly held against the extension 7 which in its turn is tightly held against the top of the cap 9.

10 It is to be understood that the bottom of the wick 6 touches the fabric 6'.

Hence, when the device is inverted, a substantial quantity of the perfume is sucked up by the wick 6 and also to a certain extent by the intermediate fabric 6'. The extension 7 and the porous washer 8 take up some of the fluid by means of capillary attraction, so that when the head 4 is rubbed or pressed against any object, so as to compress the washer 8 and the fabric 7, the fluid is pressed out of the pores of the said washer 8 and is thus spread over the desired object.

Since the wick 6 can retain a substantial 25 quantity of the fluid, and since the cork 3 tightly closes the bottle, so that the fluid absorbed by the wick 6 cannot evaporate, it is not necessary to always hold the device in the inverted position in order to apply the 30 perfume or other fluid.

In the embodiment shown in Figs. 9 and 11, the plug 5 heretofore described is replaced by a solid rod 5', the other parts being as before constructed as before mentioned. In the embodiment shown in Figs. 35 10-12, the plug consists of a hollow rod 5" having a head 4' as in Fig. 9, but a flexible porous washer 8' is now clamped between the cork 3 and a metal cap 9', the plug 5' 40 is surrounded by an intermediate strip of fabric 6' having an extension 7 and the hollow tube 5" is provided with an interior wick 10 which fulfills the same functions as wick 6 described in Fig. 5.

45 Practical tests have shown that this device will not permit any perfume to spill in any position and that minute quantities of the perfume can be spread out over large surfaces.

50 We have described preferred embodiments of our invention, but it is clear that numerous changes and omissions can be made without departing from its spirit.

1. A combined dispenser and container 55 comprising a receptacle adapted to contain a fluid, said receptacle having an outlet opening adapted to be closed by a stopper which carries a movable member therein, the bottom of said movable member being 60 normally above the bottom of the fluid, the passage between the walls of the said opening and the said member being so narrow that any outflow of the fluid is normally prevented, said movable member being so 65 mounted within the said opening that it

can be moved therein without removing it from said receptacle so as to force out a small quantity of the said fluid.

2. A combination dispenser and container 70 having a receptacle adapted to contain a fluid and provided with an outlet opening, a movable member located in the said opening, the passage between the walls of the said outlet opening and of the said movable member being so narrow that the fluid does not normally flow therethrough, an absorbent member in communication with the said passage so as to be normally saturated with the said fluid, said absorbent member and said movable member being so located that the said movable member can be moved to compress the said absorbent member and press the fluid out therefrom without removing said movable member from said receptacle.

3. A combination container and dispenser 80 having a receptacle adapted to contain a fluid and having an outlet opening, a movable member having a wick of absorbent material associated therewith and fitting into the said opening so that the fluid can only pass out of the said receptacle through the said wick, the said movable member being so mounted that the movement thereof is adapted to cause the said fluid to pass 85 through the said wick.

4. A combination container and dispenser having a receptacle adapted to contain a fluid and provided with an outlet opening, a movable member located in the said opening and having associated therewith a wick provided with a lateral portion whereby any fluid in the said receptacle can only pass out therefrom through the said wick, the said lateral portion of the said wick being 100 located between a relatively rigid part of the said movable member and another relatively rigid member, whereby when the said movable member is moved, it causes the compression of the said lateral portion of 105 the wick whereby the fluid is forced out therefrom.

5. A combined container and dispenser 110 consisting of a receptacle adapted to contain a fluid, a perforated cork located at the mouth of the said receptacle, a movable and relatively rigid member located in the perforation of the said cork and having associated therewith a wick provided with a lateral portion which is located between the 115 said movable member and the said cork, whereby the said wick can be saturated with the said fluid and the said fluid can be squeezed out of the said lateral portion by actuating the movable member.

6. A combined container and dispenser 120 having a receptacle adapted to contain a fluid and provided with a perforated cork at the mouth thereof, a hollow movable member located in the perforation of the 125

said cork, the said hollow movable member being provided with a wick which extends into the hollow part thereof and also surrounds it and has a lateral extension, the 5 said lateral extension being located between the said cork and the said movable member, whereby the said wick can be saturated with the fluid in the said receptacle and can be squeezed out of the lateral portion thereof by actuating the said movable member.

In testimony whereof we hereunto affix our signatures.

GEORGE W. BUTTON.
MILTON SIERAD.
